SIGN CONSTRUCTION

Clayton M. Hill, Chicago, Ill.

Application July 25, 1932, Serial No. 624,451

6 Claims. (Cl. 40—130)

This invention relates to sign construction and the particular aim of the invention is to produce a sign for advertising purposes, and the like, which can be easily constructed and put in operation and which will also yield better results than the advertising signs heretofore known.

At the present time, a sign comprises usually a base on which are painted the characters. Electric lamps are secured to the face of these painted signs in order to illuminate the same. There are also signs known having porcelain characters provided with the usual illuminating devices. The maintenance of such signs is relatively expensive and they are subject to the attacks of the weather. The efficiency of such signs, although they might meet certain requirements, is relatively low. The paint either absorbs a great deal of the light producing a dull effect in the daylight or the finish of the sign is so that a glare effect is produced. Broadly speaking, such signs are quite expensive as far as maintenance is concerned, their life is relatively short, and there is no provision for adjustability of the individual characters according to the requirements of the vision from the principal angle of approach. Due to the glare effect or, rather to say, due to the light absorbing effect of the sign, the expense for illumination is quite considerable.

It is the purpose of my invention to produce a sign which is easily fabricated and is easily put in operation, requiring less maintenance and producing a better effect with less expenditure for illumination. As an additional advantage, my invention provides for adjustability of the individual sign characters or of an entire sign, as the case may be, relatively to the principal angle or angles of approach.

The objects outlined briefly above are obtained by employing a metallic sign body which can easily be fabricated or stamped out of single pieces according to the size of the sign body. The surface may be pounded, corrugated in part or in toto, or it may be polished or otherwise finished according to the purpose to which the sign body is to be put. Chromium plated copper sheets may be used or other metal sheets may be employed and provided with a surface coat of chromium, or the like. The advantages obtained by the use of such metallic sign bodies are numerous. In the first place, such a metal sign is less subject to corrosion than a painted sign. It can be easily produced since machine processes can be employed to a larger extent. Such a sign body is obviously superior to a porce-

lain body since it is less subject to breakage. Concerning the light reflecting qualities of a metallic body, these are well known to be superior to any other material particularly in view of the fact that they can be more easily controlled than is the case with other materials.

The sign body, according to my invention, may be mounted so that it can be adjusted partially or totally relative to the base. This adjusting or tilting feature will permit to position a sign character or an entire sign with respect to a certain angle in the line of approach, or relative to illuminating devices throwing the light upon the sign in a certain angle.

Illuminating devices of any known kind may be easily secured to the sign characters or to the entire sign constructed in accordance with my invention.

Existing signs can be easily converted by securing my novel sign characters over the face of an old sign as will be more fully described as the description progresses.

A sign as contemplated by my invention can be readily produced at approximately the same cost which must be expended for signs of about the same size. The advantages resulting will be obvious when considering the foregoing outline. I have also found that a substantial amount can be saved by the use of my sign construction relative to the expenditure necessary for illumination. My sign can be adjusted to take full advantage of the existing natural light conditions and will yield a maximum effect particularly without any input as long as these natural conditions prevail. In other words, my sign requires little or no illumination during daylight since I take advantage of the properties of the material and since I adjust the angle of the sign to the natural environment. Expenditures for repair and maintenance will be less as will be apparent from the above and from the description which is yet to follow.

Embodiments of the invention are shown in the accompanying drawings forming part of this specification.

In these drawings
 Fig. 1 shows a fabricated or stamped character;
 Fig. 2 shows a side view of this character;
 Fig. 3 shows an end view of the character;
 Fig. 4 shows a cross section along the lines

4—4 of Fig. 1;
 Figs. 5 and 6 show sections of a character wherein the surfaces are shaped convex or concave, respectively;

Fig. 7 shows a character mounted on a base and provided with an illuminating device;

Fig. 8 is a somewhat enlarged section along the lines 8-8 of Fig. 7 showing how this character is mounted in substitution of a character of an existing sign;

5 Fig. 9 illustrates one method of adjustably mounting the sign relative to the base;

Fig. 9A shows a modified plug to be used with the embodiment illustrated in Fig. 9.

10 Figs. 10 and 11 show a substantially flat character made in accordance with my invention particularly for lamp lettering;

15 Figs. 12 and 13 show a partial top view and a cross section, respectively, of a border design for a sign, this border being adjustable perpendicularly to the base; and

Figs. 14 and 15 show another border for a sign which is tiltable or adjustable.

Now referring to the drawings, Figs. 1, 2 and 3, these figures show a simple sign which may be 20 made from a suitable metal such as chromium plated copper or the like. The sign has a face 10 and the edges 11 and 12 thereof are formed at an angle to the face so that the sign can be neatly and easily attached to a base. The width of these 25 overlapping edges 11 and 12 relative to the base of the sign body may be varied according to the effect which is to be achieved. It might be desirable, for example to mount the sign in a certain angle. In this case, the width of the edges 30 or flanges will determine the angle of the sign on the base. It is understood, of course, that only parts of the edges may be left, leaving socket-like projections on the sign body which will determine the angle thereof on the base.

35 The face of such a sign may be concave such as is indicated in Fig. 5 by the numeral 13 or it may be convex as is indicated in Fig. 6 by the numeral 14.

40 The surface, that is, the face of the sign may be pounded, corrugated or polished, or provided with ornaments as desired.

I have found that a chromium surface is the best for the effect which is to be achieved. It is 45 understood, of course, that I do not desire to be limited to any particular metal in realizing my invention. It is entirely possible to use any one of a great number of easily fabricated metals and to produce my signs from sheets of such metals and provide a metallic or other coat thereon by 50 electrolysis or paint in such manner that the effect which is desired is actually achieved.

In Figs. 7 and 8 I have shown the manner in 55 which such a sign may be mounted. This embodiment also indicates the conversion of a lamp sign to a gas sign. The novel metal letter 15 may be produced in accordance with the remarks previously made. It may be provided with the flanges or overlapping edges as indicated at 16. If desired, these edges or flanches may be made 60 of different width as explained previously in order to achieve the tilting effect of the character relative to the old sign metal 17 which, in this case, is used for the base. The lamp sockets indicated at 18, 19 and 20 may be utilized for securing the character 15 by inserting therein wooden plugs such as 21, 22 or 23. The sign body 15 is then secured to these wood plugs by means of wood screws such as 24, 25 and 26. All other sockets may remain with wooden plugs screwed 70 into the socket bases wherever needed to give a secure mounting for the novel sign letter. Porcelain bushings such as 27 and 28 are secured at the places indicated by removing the corresponding lamp sockets from the sign metal 17. These 75 porcelain bushings are employed for securing the

electrodes 29 and 30 of the gas tube 31. The supports 32 and 33 for the gas tube 31 may be secured on the sign body as shown. A trough 34 may be attached to the sign body if desired. The tilting or focusing of the sign body 15 may be, in this case, it will be remembered, determined by the width of the flanges 16 on the sign body. For example, if the sign letter is to be tilted forward, the upper border will be made wider than the lower border.

80 Referring now to Fig. 9, this figure shows means for adjustably securing a sign body or character 35 to a base 36. This means comprises a member 37 which may be tubular and provided with an external thread as shown. This member 37 is projected through a corresponding opening in the base 36 and secured thereto by means of nuts such as 38 and 39 with washers 40 and 41 interposed in the usual manner. It is thus possible by operating these nuts to move the elongated member 37 perpendicularly to the base 36. At the front end of the member 37 may be inserted a wooden plug 42 and secured to the face of this wooden plug 42 may be the sign body 35 by means of the wood screw 43. A washer 44 may be used, if desired. The sign body or character is thus attached to the base 36 and can be focused or tilted in any angle relative to its environment.

85 The structure shown in Fig. 9 and just described may be used either independently or conjointly with the flange provisions previously described. If the mounting shown in Fig. 9 is adopted, for example in the structure discussed in connection with Figs. 7 and 8, the flanges 16 will limit the possible adjustment of the sign character in one direction, namely, toward the base, thus positively and accurately determining the focusing of the sign, since the borders, which can be of predetermined widths, will act as stops for the sign against the base. Focusing away from 100 the base can be accomplished by means of the structure shown in Fig. 9. This focusing structure can also be used for solely supporting the sign and tilting it in a predetermined angle to the base. One or the other border strip may or 105 may not contact the base, as the case may be. If the means shown in Fig. 9 is used when taking advantage of the flange provisions on the sign character, the margin of adjustment will be somewhat greater than would be the case if a sign 110 with certain borders would be supported rigidly on a base. This adjusting means may also be utilized for serving in the manner of a socket for the electrodes in case of a gas illuminated sign such as discussed in connection with Figs. 7 and 115 8. It is merely necessary in this case to provide a larger wood plug 42 which, in this case must, of course, be tubular. This plug will take on its rim the wood screw 43 and will permit the insertion of the electrode through the member 37. 120 This embodiment is shown in Fig. 9A. The modified tubular plug 42' is carried by the tubular member 37' which is perpendicularly adjustable on the base as already explained in detail. The sign character 35' is secured by screws 43' to the 125 outer face of the rim of the plug 42'. The electrode 29' projects through the tubular member 37' and the gas tube 31' is joined thereto. The flanges or edges of the sign character may be of different width if desired. This is indicated 130 at 16' and 16''. The face of plug 42 may be cut at an angle, if desired. The use of wood plugs for attaching the sign furnishes the advantage of accurate lining up. The sign is simply put on 135 the surface of the wood plugs attached to the base, 140

145

150

and then secured by the screws in proper position. If metal plugs were used or plugs with predetermined threaded openings for screws to hold the sign, it would be necessary to drill the holes on 5 the sign in advance. This would introduce complications and would cause great expense in installing the sign.

When it is desired to convert a sign for lamp lettering, the structure shown in Figs. 10 and 11 10 may be used. I have shown in this case a substantially flat letter 45 with socket holes punched out to allow the reflectors to be placed over the old lettering. The sockets 46, 47 and 48 take the lamps. The sign body 45 is secured to the 15 base or to the old sign metal 49 by means of screws 50 and 51 as shown. If the same letter is adopted for new work, the sockets may be mounted on the sign body or character directly. By using this structure, it is possible to employ 20 less powerful lamps in order to achieve the same and even a better effect.

The remaining figures of the drawings show particularly border strips for a sign. For example, Figs. 12 and 13 show a base 52 to which is secured a strip 53 by means of a cover strip such as 25 54. It may be desirable to focus or tilt the edge of this strip partially or all around the sign in order to get a particular reflection or an illuminating effect which could not be achieved in 30 any other plane of the border strip. In order to do this with the least expenditure, I employ wedges such as 55 which are driven in from the side thereby lifting part of the border strip as shown in Fig. 13. Lamp sockets such as 56 and 35 57 or gas tubes such as 58 and 59 may be secured over the face of the border strip for the purpose of illumination. The entire strip may be adjustably secured if desired by taking advantage of the structure discussed in connection with Fig. 9. 40 Figs. 14 and 15 illustrate the same idea applied to a strip which is tilted or focused in a predetermined manner on either side as indicated at 60 and 61. The central portion 62 may again be secured either permanently or adjustably to the 45 base 63 by means of a cover strip 64 or by using suitable sockets or washers. The wedges 65 and 66 are driven in from either side of the strip material thus tilting and focusing the same in the desired direction. Lamp sockets 67, 68 and 69 50 or gas tubes 70, 71 and 72 may be mounted as desired for obtaining the most advantageous illumination. If desired, the wedges 65 and 66 and the wedge shown in Fig. 13 may be secured in place by separate or integral provisions such as 55 indicated in the drawings.

Changes may be devised without altering the spirit of my disclosure. I, therefore, want to have it understood that I have disclosed specific embodiments of my invention only for the purpose of illustration and not for the purpose of limiting the scope of the disclosure. What I believe is distinguishing from the art and what I desire to have protected by Letters Patent is particularly pointed out in the appended claims.

What I claim as my invention is:

1. In a sign of the character described, a base, a metallic sign body for attachment to said base, a border strip for attachment to said base, means cooperating with said sign body and said base for adjusting said sign body perpendicularly to said base, and means cooperating with said border strip and said base for tilting said strip partially relative to said base.

2. A sign of the character described comprising, a base, tubular members secured to said base in perpendicularly adjustable relation thereto, a carrier secured to each of said members, and a metallic sign body secured to said carriers.

3. A sign of the character described comprising, a base, tubular members secured to said base in adjustable relation thereto, plug means carried by each of said members, a metallic sign body secured to said plugs, and illuminating means secured over the face of said sign body.

4. A sign structure comprising, in combination, 105 a sign character, a base therefor, and means for securing said character adjustably on said base, said means including a tubular member, a plug carried thereby for receiving said character, and means for securing said member in movable co- 110 operation with said base.

5. In a sign structure of the class described, a base, a carrier secured to said base and being perpendicularly adjustable thereto, a sign character mounted on said carrier, electrode means 115 projecting through said carrier, and illuminating means mounted over the face of said character and cooperating with said electrodes.

6. In a sign structure of the class described, a base, carrier means secured to said base and 120 being perpendicularly adjustable thereto, character means mounted on said carrier means, stop means integral with said character means for defining the position of said character means relative to said base in one end position thereof, 125 electrode means projecting through said carrier means, and illuminating means secured over the face of said character means and cooperating with said electrode means.

CLAYTON M. HILL. 130
